Herman G. Graubner, New York, N.Y., assignor to Union Carbide Corporation, a corporation of New York

Filed Apr. 8, 1960, Ser. No. 60,104

Term of patent 14 years

(Cl. D48—24)

Fig. 1.

FIG. 1 is a front perspective view of a flashlight showing my design;

FIG. 2 is a reduced side elevation thereof as seen from the opposite side of FIG. 1; and

FIG. 3 is an enlarged partial section along the line 3—3 of FIG. 1 showing the transverse configuration of the top of the handle member.

The rear end of the handle member and the battery casing are substantially plain.

I claim:

The ornamental design for a flashlight, substantially as shown and described.
